UNITED STATES PATENT OFFICE.

VICTOR WINQUIST, OF ROCKFORD, ILLINOIS.

REED HOLDER AND PROTECTOR FOR MUSICAL INSTRUMENTS.

1,016,055.

Specification of Letters Patent.

Patented Jan. 30, 1912.

Application filed September 14, 1911. Serial No. 649,376.

To all whom it may concern:

Be it known that I, VICTOR WINQUIST, a citizen of the United States, residing at Rockford, in the county of Winnebago and 5 State of Illinois, have invented certain new and useful Improvements in Reed Holders and Protectors for Musical Instruments, of which the following is a specification.

The object of this invention is to construct a holder and protector for the reed of musical instruments which can be readily detached from the mouth piece of the instrument.

In the accompanying drawings, Figure 1 is a side elevation. Fig. 2 is a plan view. Fig. 3 is a section on line *a a* Fig. 2. Fig. 4 is a section on line *c c* Fig. 1. Fig. 5 is a section on line *b b* Fig. 1. Fig. 6 shows the ends of the band separated.

20 The mouth piece 1 of the musical instrument is of the usual construction. A band 2 has a central opening 3, and the ends of the band are connected by the lip 4 located in one of the slots 5. By means of the slots 25 the band can be adjusted to fit various sized mouth pieces. A pad comprises the plate 6 which holds the felt or lining 7. A rivet 8 is connected with the plate and passes through the opening 3 in the band 2, and 30 supports a thumb wheel 9 loosely. A coiled spring 10 has one end connected to the thumb wheel and its other end is located beneath the band. By turning the thumb wheel the spring is rotated which will cause 35 the pad to be moved toward or away from the band.

The band is placed over the end of the mouth piece, and the reed 12 is located in contact with the mouth piece and beneath 40 the pad. By turning the thumb wheel, the pad is moved against the reed thereby clamping it in position in connection with the mouth piece. The pad is yieldingly supported by the band and the lining which is 45 flexible will accommodate itself to the surface of the reed so that it will not be forced out of position.

It is quite essential that the thin end of the reed be protected against hard usage 50 and kept moist so that it will not split or warp. For this purpose I have provided a bail 13 having its ends formed with hooks 14 which are located in openings 15 in the

band. This bail supports a plate 16 which has a depending lip 17. A pad 18 of felt or 55 other suitable material is connected to the plate 16. The bail is turned so that the pad 18 will rest on the free end of the reed and held in this position by the lugs 19 extending from the band. When the instrument is being played upon the bail is turned free of the reed as shown at Fig. 1, and will be held in this position by the lugs 20 extending from the band. The pad 18 is moistened with water which, when contacting 65 with the reed will keep it moist.

I claim as my invention.

1. The combination of a mouth piece for musical instruments, a reed therefor, a band encircling the mouth piece, a pad resting on 70 the reed, and adjusting devices connecting the pad and band.

2. The combination of a mouth piece for musical instruments, a reed therefor, a band encircling the mouth piece, a pad resting on 75 the reed, a stud connected to the pad and passing through the band, a thumb wheel loosely supported by the stud and a coil spring connected to the thumb wheel and engaging the band.

3. The combination of a mouth piece for musical instruments, a reed therefor an adjustable band encircling the mouth piece, a pad resting on the reed, and adjusting devices connecting the pad and band.

4. The combination of a mouth piece for musical instruments, a reed therefor, a band for holding the reed in connection with the mouth piece, and a protector pivotally connected to the band and adapted to cover the 90 reed.

5. The combination of a mouth piece for musical instruments, a reed therefor, a band for holding the reed in connection with the mouth piece, a protector pivotally connected 95 to the band and adapted to cover the reed, and lugs extending from the band with which the bail engages.

In testimony whereof I have hereunto set my hand in presence of two subscribing witnesses.

VICTOR WINQUIST.
